UNITED STATES PATENT OFFICE.

THOMAS A. HUTSELL, OF SPOKANE, WASHINGTON, ASSIGNOR TO THE HUTSELL MOTOR COMPANY, OF SPOKANE, WASHINGTON.

INTERNAL-COMBUSTION ENGINE.

1,391,189.

Specification of Letters Patent. Patented Sept. 20, 1921.

Application filed January 3, 1920. Serial No. 349,283.

To all whom it may concern:

Be it known that I, THOMAS A. HUTSELL, a citizen of the United States, residing at Spokane, in the county of Spokane and 5 State of Washington, have invented certain new and useful Improvements in Internal-Combustion Engines, of which the following is a specification.

The present invention relates to improvements in internal combustion engines and 10 particularly to the construction of piston and cylinder, and also to the construction of the lubricating means for oiling the piston in its reciprocation in the cylinder.

15 The primary object of the invention is to so simplify the construction and operation of the engine by reducing the number of parts in its assembly in order that its manufacture may be facilitated and its cost 20 of production reduced to a considerable degree, as well as to enhance the efficiency of the engine. To this end the invention involves the utilization of an inverted piston 25 of which the firing stroke is utilized on its upward movement, and in constructing this specially formed piston with a hollow or tubular stem for transferring the fresh charge of fuel to the compression and ignition end of the cylinder, and also for utilizing 30 the hollow stem in conjunction with the oil pipes for distributing the lubricating oil between the walls of the piston and cylinder, all as will be hereinafter more fully pointed out and claimed.

35 In the accompanying drawings one complete example of the physical embodiment of my invention is illustrated, the parts being combined and arranged according to the best mode I have thus far devised for the 40 application of the principles of my invention. The drawings merely exemplify a preferred structure and it will be understood that alterations and changes may be made in the illustrated structure within the scope 45 of my claim without departing from the spirit of my invention.

Figure 1 is a vertical, transverse, central sectional view of an internal combustion engine embodying the principles of my invention, the water jacket and other incidental features of the usual gas engine being omitted as not necessary for a clear understanding of the invention.

Fig. 2 is a similar view, but taken at right

angles to Fig. 1, showing also a portion of 55 the crank case of the engine.

In the preferred form of the invention as illustrated in the drawings the engine embodies the usual crank case 1 upon which is supported the engine base 2 in the nature of 60 a casting with an integral, vertical, central guide tube or sleeve 3 in which the hollow tubular stem 4 of the inverted piston 5 reciprocates with the movement of the piston, and thus the movement of the stem is 65 stabilized and guided, as it transmits movement to the connecting rod 6 pivoted there- to and connected with the crank shaft of the engine not shown.

The cylinder 7 is in the form of a single 70 casting closed at the upper end and open at its lower end and securely attached, as by bolts as usual to the engine base, the cylinder, as illustrated being somewhat elongated and provided with the gas intake port 75 8 and a pair of exhaust ports 9 as usual.

The customary packing rings 10 are utilized in the piston and similar packing rings 11 are provided for the piston stem, for movement in the cylinder and sleeve respectively.

The fuel charge to the cylinder is received through the intake 8 in the wall of the cylinder and passes downwardly through the hollow piston stem and from there the gas 85 is distributed through the radial passages 12 extending outwardly from the interior of the stem and adapted to register with complementary passages 13 in the upper end of the engine case which passages open into 90 the bottom of the cylinder. Thus the intake of the fuel charge occurs when the inverted piston is in lowermost position and the two passages 12 and 13 are out of alignment and of course not in communication. On the 95 up stroke of the piston the charge is compressed in the upper end of the cylinder and finally in the inverted piston and forced downwardly through the piston stem and through the passages into the lower or ignition end of the cylinder, the position of the parts in Fig. 1 indicating this condition. On the next down stroke of the piston the charge is compressed and may then be ignited in usual manner, from the spark plug S, the 105 explosion of the charge taking place below the piston head and forcing the piston up on the firing stroke, the exhaust gases passing

out through the exhaust port or ports 9. Thus the intake and exhaust ports and the complementary gas passages 12 and 13 are controlled and regulated by the action of 5 the movement of the piston and its stem which govern the movement of the fresh and spent gases, the packing rings preventing leaks of gas as usual.

Near the lower end of the hollow piston 10 stem a transverse partition 13' is provided to close the stem against passage of fresh fuel charges, and also to provide means for communication with the lubricating oil passage or port 14 in the lower end of the engine base, which receives lubricating oil 15 from the oil pump as usual, and in the partition a radial oil passage 15 is provided opening out at the periphery of the stem and in line to register with the oil inlet passage 20 or port 14 in the engine base. An oil pipe 16 is screwed into the partition 13' with direct communication with the passage 15, and this pipe extends up through the tubular piston stem and projects a suitable distance 25 in the inverted piston where it terminates and is provided with radiating branch oil pipes 17 whose ends pass through the walls of the piston, and open at the periphery of the piston. In addition to performing their 30 function of conveying the lubricating oil to the adjoining walls of the piston and cylinder, these pipes 17 brace and hold rigid the vertical oil pipe or stand pipe 16 and retain it in place in the piston and stem, 35 the lower end of the stand pipe of course being rigidly supported in the stem partition as described. With each reciprocating movement of the piston and stem, the passages 14 and 15 are alined and register and 40 lubricating oil is forced therethrough, and thence through the stand pipe and distributed through the radial branch pipes to

the piston and cylinder walls, thus uniformly and continuously lubricating the contacting surfaces, not only of the piston and cylinder, but also of the stem and engine base, for it will be evident that these parts also are thus lubricated. 45

From the above description taken in connection with my drawings it is evident that 50 I have provided an efficient and powerful engine in which the fuel charge is first compressed above the piston by an upstroke of the latter thus reducing by approximately one half the area of the cylinder on the compression stroke, and this compressed charge is then passed through the hollow stem into the firing end of the cylinder, which has previously been emptied of the spent or 55 exhaust gases, where it is ignited in usual 60 manner, and the engine performs the usual functions of this type of motor in a simple but efficient manner.

What I claim is—

The combination with a tubular cylinder 65 and piston support and its cylinder and combustion chamber, of an open inverted piston, a hollow piston stem in said support, a partition closing the lower end of said stem and an oil pipe threaded therein with its 70 upper end in the piston, radiating branch pipes from said oil pipe passed through the walls of said piston, said partition having an oil passage extending from the lower end of the oil pipe and said base having a 75 supply passage adapted to register therewith, intake and exhaust ports to the cylinder, and means for establishing communication for a fuel charge between the combustion chamber and hollow piston stem controlled by the movement of the stem. 80

In testimony whereof I affix my signature.

THOMAS A. HUTSELL.
